UNITED STATES PATENT OFFICE.

MARTIN L. SNYDER, OF RIVERSIDE, CALIFORNIA.

NAIL-HOLDING DEVICE.

1,198,077.

Specification of Letters Patent. Patented Sept. 12, 1916.

Application filed May 2, 1916. Serial No. 84,954.

To all whom it may concern:

Be it known that I, MARTIN L. SNYDER, a citizen of the United States of America, residing at Riverside, in the county of Riverside and State of California, have invented new and useful Improvements in Nail-Holding Devices, of which the following is a specification.

The present invention relates to improvements in nail holding devices and particularly to the delivery nozzle of such devices.

The purpose of the invention is to provide a delivery nozzle for a magazine tube in which nails are held, preferably in a belt around the waist worn by a carpenter or other mechanic, and from the nozzle the nails are to be taken, one at a time by the carpenter. The nozzle is at the end of the belt or tube, preferably at the right side toward the front of the wearer so that he may take one nail at a time from the nozzle in his left hand, either by its head or by grasping the shank of the nail, while holding the hammer in his right hand. By this means the nail may be quickly handled in position for use, one by one as needed, without the annoyance to the carpenter of holding several nails while driving but one.

The invention consists in certain novel combinations and arrangements of parts by means of which the nails are ejected to the delivery portion of the nozzle and retained there, as will be hereinafter more fully described and claimed.

In the accompanying drawings I have illustrated one complete example of the physical embodiment of my invention, constructed according to the best mode I have so far devised for the practical application of the principles of my invention.

Figure 1 is a vertical longitudinal sectional view of the delivery nozzle, showing also a portion of a tube from which the nails are supplied to the nozzle. Fig. 2 is a top plan view of Fig. 1. Fig. 3 is a perspective view of the nozzle detached. Fig. 4 is a transverse sectional view of the nozzle.

For the purpose of illustrating the adaptation of my invention I have indicated as 50 1 a portion of a magazine tube in which the nails are supplied to the nozzle, the tube being provided with a slot 2 at its under side through which the nails 3 may pass by gravity, and in the slot the nails are suspended by their heads 4. A spring detent 5 with a transverse bar 6 and finger 7 is

designed to hold the nails in the open end of the magazine tube until it is desired to permit the nails to pass into the nozzle.

As illustrated the nozzle is preferably made up of two metallic, spaced, parallel plates 8 and 9 with guide flanges 8' and joined at one end at the upper edge by the cylindrical sleeve 10, which has a pair of bevel edges or cam faces 10' over which the cross bar 6 of the spring detent passes to lift the detent and permit passage of nails from the magazine tube 1 to the nozzle. The rear end of the nozzle is open and cut out as at 11 to accommodate the first finger and thumb of the carpenter, but a bottom 12 braces the two plates 8 and 9 at the underside. The nails are suspended by their heads in the nozzle and pass from the magazine tube along the ledges 13 formed inside the sleeve 10, and then when they emerge from the sleeve the nails continue along in the nozzle, their heads sliding along on the upper edges 13' of the two side plates 8 and 9. Each of the side plates is provided with an opening or slot 14, arranged opposite each other and located near the upper edge of the plates.

The slots in the side plates are to accommodate the ejecting device of the nozzle, and this device is carried by the oscillatable housing made up of the two side plates 15 and 15', the housing being open at both ends and the top and incasing the nozzle at one end thereof. The closed bottom 16 of the housing is located in an opening in the bottom 12 of the nozzle and under the lower edges of the two plates 8 and 9, and the two perforated ears 17 and 17' at the ends of the bottom 16 are adapted to receive the pivot or rock pin 18 suspended in perforated ears 19, integral with the walls of the open portion of the bottom 12 of the nozzle. The housing is adapted to rock on its pivot 18 by pressure from the hand or fingers, and the side plates 15 and 15' are provided, one with a retaining detent 20 and the other with an ejecting pawl 21, the detent being normally held in the slot 14 in plate 8, and the pawl moving through the slot in plate 9. By means of the flat leaf spring 22 held between the plate 15 and plate 9 and secured under the bottom 16 as by soldering, the detent 20 is held in normal position across the space between the two side plates 8 and 9, the pawl 21 being held out of the path of movement of the nails, as in Fig. 2. When,

however, the plate 15 of the housing is pressed against spring 22 as by the forefinger of the mechanic, the housing is rocked on its pivot with the result that the retaining 5 detent 20 is withdrawn from the path of the nails and the ejecting pawl 21 is pushed into the path of the nails. The forefinger contacts with the upper front corner of the plate 15, so that when the plate 15 is pressed 10 toward the nozzle wall, one nail is passed between the detent 20 and the ejecting pawl 21, the nail being indicated as 3'. This nail is in position to be grasped at its head 4 by the thumb and forefinger, if desired, as they 15 manipulate the spring pressed housing and rock it upon its pivot. By preference, however, the nail is withdrawn by the forefinger and thumb at the cut away end 11 of the plates, and the spring fingers 23, 23, which 20 are fixed to plate 8 and project through slots 24, 24 therein hold the nail against exit at the end of the nozzle except when the nail is withdrawn forcibly between the thumb and forefinger. In this manner one nail at a 25 time may be taken by its head or by its shank, between the thumb and forefinger, while the other nails are kept separated and retained by the detent, thus insuring a device which is facile in manipulation, easy

of access, and accurate and efficient in performing its functions. 30

What I claim is:

1. The combination with a nozzle having an open cut away end and comprising spaced rigidly connected side plates provided with 35 slots and adapted to support the heads of nails on their upper edges, of an oscillatable housing pivoted between the said plates and consisting of oppositely disposed members having, respectively, a retaining detent and 40 an ejecting pawl operative in said slots, and spring fingers near the cut away end to retain a nail.

2. The combination with a nozzle having an opening in its bottom and comprising 45 spaced, rigidly connected, slotted, side plates adapted to support the heads of nails on their upper edges, of an oscillatable housing comprising a pair of spaced rigidly connected plates pivoted between the side plates of 50 the nozzle and provided with a detent and an oppositely located co-acting ejecting pawl operative in said slotted side plates, and a spring between adjoining plates of the housing and nozzle to hold the detent in retaining 55 position.

In testimony whereof I affix my signature.
MARTIN L. SNYDER.
